Jordan L. Mott of the City of New York
Letter Patent

9166X

The Schedule referred to in these Letter Patent as a making part of the same containing a description in the words of the said Jordan L. Mott himself of his Improvement in the construction of grates or grate bars for Stoves or Furnaces.

To all whom it may concern

Be it known that I Jordan L. Mott of the City of New York have invented an improved mode of constructing grates or grate bars for Stoves or Furnaces by means of which they are rendered more economical and the vibrating and tilting motions are obtained by a very simple arrangement of the parts, and I do hereby declare the following to be a full and exact description thereof.

I cast a circular ring or hoop that is to receive the grate and that has a projecting flange on the inside upon which projecting pieces upon the edge of the grate rest. A shank forming one of the pins or judgeons upon which the grate tilts, passes through an opening or slot left in the rim for that purpose, and has a knob or handle by which the vibrating and tilting may be effected. This slot is covered on the outside by a curved sliding piece of cast iron which prevents dust from passing through. The grate itself is cast with — a hole in its centre to receive a pin upon which it vibrates horizontally which pin is sustained by a cross bar cast upon and with the hoop. The back judgeon which forms one of the bearings upon the flange before mentioned is not diametrically opposite to the shank in front but is placed a move so far out of a line with it as to cause the grate when tilted to lift off the centre pin and to clear the cross bar, or a projecting piece may extend from the flange out of the diametrical line of the shank upon which the edge of the grate may rest when tilted, but this is not preferred as the grate will not so readily fall on the centre pin when returned to its place as it will do if properly adjusted when the judgeon is on the grate. The pin may be cast upon the grate and a hole

to eccentric lift in the crop bar, the former method however is deemed the best. When the grate is brought into the proper position for tilting, one of the projecting pieces on the grate passes through a notch in the flood. Usually make the upper side of the grate convex and curve the crop bar to correspond therewith as shown in the drawing deposited in the Patent-Office. But it may if preferred be made flat and the bar straight. I do not claim the vibrating and tilting motions as such. But what I do claim as my invention and improvement is the combination of the vibrating and tilting motions with the back eccentric lever or projecting piece, by which the grate may be lifted off and turned on to the centre pin and clear the crop bar by merely turning the hand. I also claim the particular combination of the respective parts as above described by which the grate and its bearings are delivered from the moulds in working ready position without any filing or other fitting, or the addition of any sliding bar pin or other appendage the operating parts consisting only of the grate, the ring or hoop and the cover for the opening or slot.
